UNITED STATES PATENT OFFICE

2,373,310

TUBULAR PILOT

Bruce Hayter, Santa Fe, N. Mex., assignor to Oil Devices, Santa Fe, N. Mex., a limited partnership of Illinois

Application July 11, 1941, Serial No. 401,890

3 Claims. (Cl. 158—91)

My invention relates to an improvement in pilot lights for liquid hydrocarbon burners, and has for one purpose the provision of a pilot light which shall employ the same liquid fuel supply as the burner as a whole.

Another purpose is the provision of an improved pilot light which permits a very low turn-down.

Another purpose is the provision of a pilot light which produces a minimum of smoking or carbon deposit.

Another purpose is the provision of an improved pilot light in which a pilot chamber is provided within and in communication with a pot type burner and associated with the normal liquid fuel supply means.

Other purposes will appear from time to time in the course of the specification and claims.

I illustrate my invention more or less diagrammatically in the accompanying drawings wherein:

Fig. 1 is a vertical axial section;

Fig. 2 is a section on the line 2—2 of Fig. 1;

Fig. 3 is a section on the line 3—3 of Fig. 1;

Fig. 4 is a partial section similar to Fig. 1 through a variant form of the device;

Fig. 5 is a section on the line 5—5 of Fig. 4;

Fig. 6 is a section similar to Fig. 4 of a further variation of the device; and

Fig. 7 is a similar section of a still further variation.

Like parts are indicated by like symbols throughout the specification and drawings.

Referring to the drawings, I generally indicate a burner pot having a plurality of primary air inlets 2 located at various levels in the wall of the pot. I may employ any satisfactory means for admitting secondary air, but I illustrate herein in a plurality of closely spaced secondary inlets 3 located adjacent the top of the pot. Any suitable means may be employed for supplying air through the apertures 2 and 3. I illustrate an outer housing or drum 4 which surrounds the pot 1. 5 is a flange which extends inwardly from the drum 4 and supports the top flange of the pot. 6 is an air inlet aperture at the bottom of the drum 4. 7 is any suitable fire ring having a central aperture 8. As herein shown, it may simply be superposed upon the top of the pot.

9 is a liquid fuel inlet line from any source of liquid fuel not herein shown. Any suitable valve means not herein shown may be employed for varying or controlling the flow of fuel along the line 9. It will be understood also that any ap-

propriate means for controlling the level of the fuel may also be employed.

10 generally indicates a nozzle fitting extending inwardly through an aperture 11 in the wall of 5 the drum 4 and abutting against the outer face of the pot 1. 12 is a screw threaded portion projecting inwardly into the interior of the pot. 13 is a nut whereby the fitting 10 may be secured in relation to the pot. Extending beyond the 10 screw threaded portion 12 and the nut 13 is the nozzle proper 14, placed somewhat above the bottom of the pot, and which may have its upper portion longitudinally slotted or cut away as at 15.

16 is an air tube, preferably located in the 15 space between the pot 1 and the drum 4 and extending upwardly in close proximity to the outer wall of the pot 1. Its top is open, as at 17, whereby air may pass into the fuel passage 18 of the fitting 10. 19 is any suitable cleanout plug at 20 the outer end of the fitting 10.

20 generally indicates a foraminous pilot tube. It may be supported on the floor of the pot, for example, by any suitable downwardly extending flange or flanges 21. In the form of Figs. 1 and 25 2 it is indicated as a foraminous tube having an upturned lip 22, adjacent the outer end, providing an open end for the tube which is aligned with the central axis of the pot 1. The inner end of the tube may extend about the nozzle 14 and may for example abut against the nut 13.

In the form of Fig. 4 a foraminous tube 30 may be employed, which may be clipped on the end of the nozzle, as for example, by spring fingers or the like 31. The end may be closed, as at 32, 35 or if desired, the closed end 32 may be omitted. It will be understood, of course, that the tube 30 may be supported, if desired, from the bottom of the pot, as is the tube 20.

In the form of Fig. 6 the foraminous tube 35 40 is employed, which is herein shown as open ended. It may be supported on the end of the nozzle as by spring fingers or the like 36, and it may be provided with a Venturi cone 37. It may be advantageous, in connection with this Venturi cone, 45 to employ oversize apertures 38 for locally increasing the air supply to the interior of the tube 35.

In the form of Fig. 7 the tube 35, in place of the sheet metal cone 37, is provided with a Venturi element 40, which may be fitted within the inner end of the tube.

It will be realized that, whereas I have described and illustrated a practical and operative device, nevertheless many changes may be made in the size, shape, number and disposition of

parts without departing from the spirit of my invention. I therefore wish my description and drawings to be taken as in a broad sense illustrative or diagrammatic, rather than as limiting me to my precise showing. The use and operation of my invention are as follows:

In the employment of pot type burners a liquid hydrocarbon may be supplied to the bottom of the pot, as in the forms herein shown. The liquid fuel is vaporized on the bottom of the pot in response to the heat of combustion taking place in the upper portion of the pot or above the pot. As the vaporized hydrocarbon rises, it mixes with the primary air flowing in through the apertures 2, to produce an initial mixture of air and vaporized hydrocarbon which is converted to the final combustible mixture by the secondary air flowing in through the apertures 3.

At high stages of combustion, when a full supply of fuel flows through the line 9 and the nozzle 14, the final mixture burns at or above the level of the secondary inlets 3, and the heat of combustion causes the vaporization of the fuel progressively supplied to the bottom of the pot. The fire is controlled by controlling the volume of fuel delivered from the nozzle 14. When, by the use of any suitable valve control means, the supply of the liquid hydrocarbon is reduced to a minimum, the small volume then is vaporized and burned at or about the pilot piece or shell 20 or 30.

This primary mixture of vaporized hydrocarbon and air flowing in through the air tube 16 is burned within the pilot piece 20 or 30, the function of the holes in the pilot piece being to balance the pressure inside the combustion compartment thus formed. Final combustion begins in the pilot piece or housing and extends out through the holes. The pilot piece picks up heat from the heat of combustion and radiates it back to the nozzle. The jets of flame which pass through the holes may pick up additional air outside of the pilot piece.

I find it advantageous to slot or cut away the nozzle tip, as shown at 15, and the mixture of air and hydrocarbon receives additional air as it flows along the terminal portion of the nozzle 14. As soon as high fire is desired and the flow of fuel is increased, the fuel then flows in increasing volume down upon the bottom of the pot, and the level of combustion rises as the fuel supply increases, until full combustion has taken place at or above the secondary apertures 3.

In effect I provide a rather definitely defined zone or area which is kept at a temperature considerably above the evaporation temperature of the oil, and the liquid oil flowing through the passage 18 reaches this area or zone at a temperature above vaporization. The hydrocarbon cracks but does not thereafter contact the liquid oil. As soon as the fuel is cracked, any solid particles are carried along with the air away from the liquid and are virtually in a gaseous state.

I find it desirable to make the nozzle of steel so that it will not readily transmit the heat back to the liquid hydrocarbon. I employ a nozzle which protrudes well into the combustion zone, and I make the side wall of the nozzle as thin as is possible with the necessary mechanical strength. By slotting or cutting away the top of the nozzle, as at 15, I obtain the result that the point of evaporation can be anywhere in the trough so provided without permitting the fuel to drop off as a liquid; also, without vaporizing the liquid too far back into the nozzle.

I find it advantageous also to provide a limiting means or shoulder, as shown for example at 18a, to act as a dam and to back up some of the oil in the bottom of the inlet nozzle or passage. In the event that any carbon accumulates at the back of the dam and is not swept through the nozzle by the air and fuel flowing therethrough, it has a wick action equivalent to the damming up of fuel in the bottom of the nozzle.

10 Basically, what I provide is a small smokeless oil burner operating at the tip of the main oil supply pipe. The oil is vaporized before leaving the end of the pipe, and the dry gas is mixed with air issuing from the same pipe at a velocity sufficient to stop burning back in the oil inlet. This gas and air mixture is then burned at a point near enough to the nozzle to provide the proper heat for vaporizing the oil before it leaves the nozzle. The air coming through the oil pipe or nozzle

15 supplies the primary air only, and the heat applied to the end of the nozzle supplies the means for turning the oil, gas and air into a dry gas. This mixture then receives sufficient secondary air in the pot to maintain final and smokeless combustion.

20 The structure essentially includes two parts, first, the nozzle and mixing member which carries the fuel, and the primary air, to the pot and which receives sufficient heat completely to vaporize the liquid hydrocarbon before it escapes from the nozzle. In order to keep the gas thus formed from backfiring into the nozzle, air is delivered at a rate of flow above that of flame propagation. Secondly, in order to maintain the 25 nozzle heated to a sufficient temperature for complete vaporization of the fuel, it is necessary, not only that the nozzle extend into the pot, but that means be employed to localize pilot combustion and to return heat to the nozzle tip.

25 I may find it advantageous, as in the form of Figs. 1 to 3, to carry the tube 20 to the center of the pot, and to have it discharge generally upwardly in the center of the pot. In the form of Figs. 1 and following, the end of the nozzle 14 30 extends within the end of the pilot tube 20. Under some circumstances this is not necessary. I illustrate, for example, in Fig. 4 a tube 30 which is aligned with but does not actually surround the end of the nozzle.

35 In the form of Figs. 6 and 7 I find it preferable to employ a Venturi collar within the tube to increase the speed of movement of the air outwardly across the nozzle. The nozzle in Figs. 4, 5 and 6 is not shown as actually slotted, but it 40 will be understood that it may be slotted or open at the top, as shown in the form of Figs. 1 to 3, or it may be left solid, as shown in Figs. 4 to 7.

45 In effect, after the combustible gas has been formed, I provide a supplemental combustion chamber which lies wholly within the pot itself, and I do not wish to be limited in my claims to any specific form of localizing and heat reflecting means except so far as the limitation is specifically written into the claims.

50 An important feature of my device is that the liquid hydrocarbon may be fed by gravity along the pipe, and a sufficient primary air supply is provided by natural draft alone, although under some circumstances I may wish to employ means for producing excess air pressure. In any event, the liquid hydrocarbon flows along the nozzle with the primary air supply, and the nozzle is heated sufficiently completely to vaporize the liquid hydrocarbon so that it does not escape from the nozzle.

zle in liquid condition. Any tendency to burn back into the nozzle is prevented by maintaining a rate of air flow or rate of flow of the ensuing mixture greater than the speed of flame propagation.

I claim:

1. In combination, in a pot type burner, a burner pot having a circumferential side wall, a liquid fuel pipe extending to the pot, a fuel nozzle in communication with the fuel pipe, extending generally radially and horizontally into the lower portion of the burner pot at a level adjacent the bottom thereof, and a generally radial tubular foraminous pilot member axially aligned with said nozzle and extending radially a substantially distance toward the center of the burner pot and having at its inner end a discharge aperture adapted to permit the movement of gases into the burner pot, said nozzle being adapted and located to discharge fuel into the outer end of the tubular pilot member.

2. In combination, in a pot type burner, a burner pot having a circumferential side wall and a bottom, a liquid fuel pipe extending to the pot, a fuel nozzle in communication with the fuel pipe, extending generally radially and horizontally into the lower portion of the burner pot at a level adjacent the bottom thereof, and a generally radial

tubular foraminous pilot member axially aligned with said nozzle and extending radially a substantial distance toward the center of the burner pot and having at its inner end a discharge aperture 5 adapted to permit the movement of gases into the burner pot, said tubular pilot member being supported at its inner end from the bottom of the pot and being supported at its outer end upon the fuel nozzle, said nozzle being adapted and located 10 to discharge fuel into the outer end of the tubular pilot member.

3. In combination, in a pot type burner, a burner pot, having a side wall and a bottom, a liquid fuel pipe extending to said pot, a fuel nozzle, in communication with the fuel pipe, extending generally radially into a lower portion of the burner pot, said nozzle being adjacent but above the bottom of the pot, and a tubular foraminous pilot member aligned with and in communication 15 with the nozzle and extending generally radially from the nozzle and substantially to the center of the burner pot, its outer end being positioned to receive fuel delivered from the nozzle, said pilot member having an upwardly turned terminal portion adjacent the axis of the burner pot, adapted 20 to permit the movement of gases upwardly in the center of the pot.

BRUCE HAYTER.
